UNITED STATES PATENT OFFICE.

WILLIAM P. WALKER, OF FORT SILL, OKLAHOMA.

UNDERGARMENT.

No. 894,086.

Specification of Letters Patent.

Patented July 21, 1908.

Application filed August 17, 1907. Serial No. 388,995.

To all whom it may concern:

Be it known that I, WILLIAM P. WALKER, a citizen of the United States, residing at Fort Sill, in the county of Comanche, Oklahoma, have invented new and useful Improvements 5 in Undergarments, of which the following is a specification.

This invention relates to under garments; and it has particular reference to that class 10 of under garments which are known as union suits.

Union suits, as the name implies, consist of upper and lower garments, that is to say, shirts or waists and drawers, which are permanently united together in the form of a single garment. Ordinarily, union suits, so called, are manufactured throughout of knit goods or fabric which is soft, pliable and sufficiently elastic to stretch and adapt itself to 20 the figure of a person wearing the garment, and to yield to the movements of the body. Woven material has been used for the purpose of reinforcing union garments at various points where special durability and non-elasticity is desired; for instance, around the 25 neck, and at the plackets and other points where fastening means, such as buttons and button holes are needed; but apart from such reinforcements, which are commonly used in connection with under garments manufactured 30 of knit fabrics, such union suits have been usually produced or manufactured, practically in a single piece, from knit goods. It is well known, however, that this very 35 peculiarity of construction has deterred many persons from using or wearing union suits, in spite of the fact that they are in other respects extremely desirable; the reason being found not only in the fact that the drawers 40 portion of the garment is apt to wear out long before the shirt portion, but particularly therein that very many persons dislike the clinging qualities of the knit fabrics in the lower garments.

I propose to overcome these objections, and to produce a union suit which shall be acceptable to those who object to a union suit made wholly of knit material, by making a union suit comprising a shirt portion made 45 of pliable, elastic knit goods and a drawers portion constructed mainly of relatively non-elastic textile material; the same being permanently united along the waist line so as to produce to all intents and purposes a single

garment having all the advantages and none 55 of the discomforts or disadvantages of the ordinary union suit.

With these and other ends in view, which will readily appear as the nature of the invention is better understood, the same consists 60 in the improved construction and novel arrangement and combination of parts which will be hereinafter fully described and particularly pointed out in the claims.

In the accompanying drawings has been 65 illustrated a simple and preferred form of the invention; it being, however, understood that no limitation is necessarily made to the precise structural details therein exhibited, but that changes, alterations and modifications 70 within the scope of the invention may be resorted to when desired.

In the drawings, Figure 1 is a perspective front view of a union suit constructed in accordance with the invention. Fig. 2 is a 75 rear view of the same. Fig. 3 is a detail view in elevation showing the seat portion of the drawers unbuttoned and slightly separated.

Corresponding parts in the several figures are denoted by like characters of reference. 80

The shirt portion 1 of the improved garment is made of any suitable knit fabric which is both flexible and elastic. The drawers portion 2 is made of textile material, such as the goods which is commonly known 85 as "drilling"; said drawers portion being permanently connected with the shirt portion, along the waist line by stitching, as shown at 3, or in any suitable manner; the garment being provided along the waist line 90 with a waist band 4 of drilling or other suitable relatively non-elastic material. The drawers portion of the garment is provided along the inner and outer sides of the legs with inserted strips 5 and 6, of knit goods or other suitable 95 material of a relatively elastic nature, after the fashion of the well known garments which are known as "elastic seam drawers"; said drawers portion is likewise provided with ankle bands 7 of knit goods, and with 100 an inserted seat and crotch portion 8, which is likewise made of elastic knit goods. The drawers portion of the garment is provided with the usual front placket 9 equipped with buttons and button holes or similar fastening 105 devices; and the meeting edges of the inserted seat portion 8 are reinforced by placket strips 10 of non-elastic material.

equipped with buttons and button holes or other suitable connecting means, as shown at 11.

It will be distinctly understood that the 5 shirt portion and the drawers portion of the improved garment have a permanent and unbroken connection along the waist line where the waist band 4 is provided; said waist band being stitched or otherwise secured along its 10 upper and lower edges to the shirt portion 1 and the drawers portion 2, respectively, of the garment.

By the construction herein shown and described, a union garment is provided which 15 combines all the advantages of separate garments constructed of different material with all the advantages of a union garment; and it is thus calculated to fill a want which has not heretofore been supplied.

20 I am entirely aware that single garments have heretofore been constructed in which different materials have been employed for special reasons arising out of the different nature of the material; an excellent example being the so called elastic seam drawers in which for reasons well understood the comparatively inelastic textile material employed in the construction of the body of the garment has been combined with inserted seams, crotch 25 pieces and ankle bands of comparatively elastic material, such as knit goods. I am also well aware that garments constructed mainly of elastic material, such as knit goods have been reinforced at various points by 30 means of material of a relatively non-elastic

nature. I am not aware, however, that a union garment has ever been made, previous to my invention hereof in which a body portion or shirt portion of relatively elastic material, such as knit goods, has been permanently combined with a drawers portion, the body of which is made of relatively non-elastic material, such as textile or woven fabric. The advantages of such a garment have been 40 pointed out in the foregoing specification; it 45 will be found convenient and comfortable in use, and to possess a degree of durability not possessed by the ordinary union garment constructed practically throughout of knit goods.

Having thus described the invention, what 50 is claimed as new, is:—

A union undergarment comprising a shirt portion of elastic material such as knit fabric, a drawers portion of inelastic material such as woven fabric, and an inelastic waist band 55 to which the shirt and drawers portions are permanently united, the drawers portion embodying elastic seams, centrally overlapping elastic seat portions divided from each other from the waist band downward along the 60 crotch, and inelastic strips united to the inner edges of the elastic seat portions and provided with complemental fasteners.

In testimony whereof, I affix my signature in presence of two witnesses.

WILLIAM P. WALKER.
